A. SCHEUCHZER

RAILROAD TRACK WEEDING MACHINE

Filed July 31, 1923

Inventor
A. Scheuchzer
By Marks & Clark Atty.

UNITED STATES PATENT OFFICE.

AUGUSTE SCHEUCHZER, OF RENENS, NEAR LAUSANNE, SWITZERLAND, ASSIGNOR TO FERRODESHERBEUSE SCHEUCHZER SOCIETE ANONYME, OF RENENS, SWITZERLAND.

RAILROAD-TRACK-WEEDING MACHINE.

Application filed July 31, 1923. Serial No. 654,938.

To all whom it may concern:

Be it known that I, AUGUSTE SCHEUCHZER, citizen of Switzerland, residing at Renens, near Lausanne, Switzerland, have invented 5 certain new and useful Improvements in Railroad-Track-Weeding Machines, of which the following is a specification.

In railroad-track weeding-machines known heretofore there was a plough attached to a 10 railroad car and no provision was taken to adapt the apparatus to the variable width of the embankments or to avoid obstacles such as signal- and telegraph-posts and the like.

15 In the weeding-machine according to the present invention the defects mentioned have been taken into consideration. The plough is movable in a vertical sense being supported by a parallel-lever connection projecting transversely to the rails from a truck which can be moved transversely to the rails. The plough is suspended vertically by elastic members so that it can pass 20 around obstacles projecting above the ballast.

25 In the accompanying drawing which represents one embodiment of the invention, Fig. 1 is a plan with the apparatus in operative position, the inoperative position being indicated by interrupted lines, Fig. 2 is a side elevation and Fig. 3 a front elevation.

30 On a truck not shown, channel-irons *a* are arranged transversely so as to form the path of a trolley *b* which is moved from a metor, not shown, by means of an endless chain passing over the chain pulley *d* mounted on the channel-irons and attached to the trolley. A vertical pivot pin *e* is rotatably mounted on said trolley and two parallel 35 levers *f* are hinged with their one ends to said pin *e* and with their other ends to a sleeve *g* on a pin *h* which is parallel to pin *e* and fast to one end of plough-blade *k*. An adjusting ring *o* prevents said pin from 40 slipping out of said sleeve. The other end of the blade is suspended by means of springs to the truck. These springs will maintain the blade in its normal working 45 position shown in Fig. 1, while the parallel-lever connection is kept suspended by a

cable attached to the truck, which cable provides for the necessary tractive force for pulling the plough through the ballast, said lever-connecting being free to swing on the pins *g* whenever a sleeper projecting from the track more than normally or any other 55 obstacle would obstruct the path of the plough.

Owing to the parallel-lever-connection *e*, *h*, *f*, *f* the plough is adapted to follow the unevenness of the embankment and may be adjusted in a vertical plane. The amount to which the plough extends to the outside of the rail-track and which determines the 60 width of the weeded surface may be controlled by moving the trolley on the truck.

Having now fully described my invention and the manner to which the same is to be performed, that which I claim as new and wish to secure by Letters Patent is:

1. In a weeding machine, guide rails, a carriage mounted to travel between the guide rails, a parallel lever device adapted to swing in a vertical plane, a vertical pin on the carriage pivotally supporting the 70 inner end of the lever device, and a plow connected with the outer end of the parallel lever device.

2. In a weeding machine, track rails, a carriage mounted for sliding movement 80 between the track rails, an upright pivot pin carried by the carriage, a parallel lever device pivotally connected at one end with said pin, a sleeve connected with the opposite end of the parallel lever device, and a plow supported by said sleeve.

3. In a weeding machine, track rails, a carriage mounted for sliding movement between the track rails, an upright pivot pin carried by the carriage, a parallel lever device pivotally connected at one end with said pin, a sleeve connected with the opposite end of the parallel lever device, a plow, and an upright pin carried by the plow 85 pivotally received in the sleeve and permitting swinging movement of the plow in a horizontal plane.

In testimony whereof I affix my signature.

AUGUSTE SCHEUCHZER.
